UNITED STATES PATENT OFFICE.

HANS WIEDERKEHR, OF WINTERTHUR, SWITZERLAND, ASSIGNOR TO THE FIRM OF SCHWEIZERISCHE LOKOMOTIV- & MASCHINENFABRIK, OF WINTERTHUR, SWITZERLAND.

REVERSING DEVICE FOR ENGINES WITH INTERNAL COMBUSTION.

1,085,653.

Specification of Letters Patent.

Patented Feb. 3, 1914.

Application filed April 28, 1913. Serial No. 764,076.

To all whom it may concern:

Be it known that I, HANS WIEDERKEHR, a citizen of the Republic of Switzerland, residing at Zürcherstrasse 17, Winterthur, Switzerland, have invented new and useful Improvements in Reversing Devices for Engines with Internal Combustion; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to reversing devices for two cycle internal combustion engines. In such engines the reversing of the direction requires one after another the following operations: starting the engine by means of compressed air; changing from the starting to the working position; power regulation by changing the quantity of fuel. It is already known to produce all these operations by means of a hand controlled rotary member but the present invention differs from the usual devices on account of the peculiar conformation of the rotary member. This member has the form of a disk or drum provided with curved tracks into which work pins, which are connected with the relative movable elements of the engine.

The accompanying drawings represent an example of the object of the invention.

Figure 1 is a side view of the reversing device with parts in vertical section. Fig. 2 is an elevation of the controlling disk with the curved tracks. Fig. 3 is a vertical section through the distributing shaft and the shaft of the valve levers, with a part of the engine cylinder in vertical section. Fig. 4 is a vertical section through the starting valve. Fig. 5 a vertical section through the fuel valve or the valve for the charge. Fig. 6 is a portion of the controlling disk on an enlarged scale. Fig. 7 a vertical section of Fig. 6. Fig. 8 represents the arrangement of the fuel pump in vertical section and Fig. 9 is a detail of this pump.

The same letters refer to like parts in the several figures.

S designates a controlling disk, which can be turned by means of the handle H. This disk is provided with curved grooves K₁, K₂

and K₃, into which work rolls at the ends of levers M, N, T, which serve to move the reversing means. By means of a fixed disk E, provided with notches in its periphery, and a pawl h at the handle H, the controlling disk can be fixed in its position. Through the curved groove K₁ and the bell-crank lever M the distributing shaft W may be axially displaced. This distributing shaft W carries pairs of cams A_v, A_r and B_v, B_r for controlling the starting valves and the fuel valves; the cams A_v and B_v are designed for the going forward and the cams A_r and B_r for the reversing of the engine.

The starting valve c (Fig. 4) has the usual arrangement; for the supply of compressed air, this valve is connected through a pipe d with a reservoir in the well known manner. The valve g for the charge (Fig. 5) is also of a usual arrangement; this valve is connected with the fuel pump through the pipe e, while f designates a pipe for the supply of the compressed air of the charge.

By means of the curved groove K₂ and the lever N, the shaft U of the cam levers a, b may be turned, so that the cam levers a and b for the starting and fuel valves, eccentrically mounted on the shaft U, take either a position in which the lever rolls O_a and O_b will not be touched by the cams and the valves consequently not be moved (position given with full lines in Fig. 3), or in a position in which the valve will be moved according to the starting and working position.

By means of the curved groove K₃ of the lever T and the shaft P, the fuel pump will be put into the working position and also the quantity of fuel regulated. The driving means of this fuel pump have a shaft p which is actuated for instance through the main shaft of the engine and is connected with the distributing shaft W through actuating gears q. On the shaft p are mounted eccentrics r and s, which are connected by links t and u respectively with the piston i of the pump and with a reciprocated rod m.

h is the casing of the fuel pump, l the delivery vent and o the suction valve; v is the suction chamber and y a pipe to supply fuel to this chamber. The suction valve is controlled through a bell-crank lever z, articulated on a bolt z, which is eccentrically mounted at the end of the shaft P. This shaft end with the bolt z reaches into the

suction chamber v . On the one arm of the bell-crank lever n rests the suction valve, while the other arm lies against the end of the reciprocated rod n .

- 5 Position I (Fig. 2) of the handle corresponds to the stop position of the engine. To start the engine in the forward direction, the controlling disk S will be turned in the direction of the arrow V , whereby the distributing shaft W will first be axially displaced and the cams A_v for the starting valve and B_v for the fuel valve arrive under the corresponding levers a and b (position II_v). By further turning the controlling disk in the same direction, the cam lever shaft U will also be turned and the levers a and b moved so that the starting valve can now be moved into the open position and compressed air can enter the cylinder for starting the engine (position III_v); by further turning the controlling disk S , the distributing shaft will be further axially moved, whereby the starting cams come out of reach of the levers a , the starting valves consequently now remain closed; the fuel cams B_v remain under the corresponding levers b . Finally the fuel pump will be put into the working position through the shaft P for more or less power corresponding to the position of the controlling disk. IV_v is the position for the greatest power. The controlling disk being in such a position, that the eccentric bolt z on the end of the shaft P has its highest position, then the suction valve o will be maintained open through the reciprocated rod m and the bell-crank lever n during the whole delivery stroke of the piston i and no fuel will be furnished to the engine. When by means of the controlling disk the shaft P is turned and thereby the bolt displaced downward, an interspace is formed between the valve o and the bell-crank lever n ; this interspace is increased as the bell-crank levers are lowered; in the lowest position the valve remains unactuated during the whole delivery stroke; in the intermediate positions, the suction valve will be maintained open during a greater or smaller portion of the delivery stroke. The eccentricities s and r are at 180° to each other. The same operations take place when the controlling disk is turned in the direction of the arrow R , *i. e.* when the engine is to be put from the stop position on going backward.
- 55 When the engine is to be brought from the working position, *viz.* from going forward or backward into the stop position, the cited operations would take place in inverted succession by turning the controlling disk backward, as far as the axial return of the shaft W is made possible, for instance through an inclined ramp at the starting valves A_v , A_r . Of course compressed air would again be admitted when the lever N passes over the starting position III_v or III_r . Now in order

to prevent this and also to prevent a loss of compressed air, the controlling disk is provided with automatic guide tongues k , which are fixed on levers X and held in position through springs F connected to the levers X . The tongues are arranged at the ends of an inner branch of the groove K_2 in each half of the disk S ; through the guide tongues k , the roll at the end of the lever N is prevented from entering the outer branch of the groove K_2 , and will be rather forced into the inner branch. The latter is so conformed, that the cam lever shaft will be turned back sooner and the rolls O_a and O_b of the levers a and b come out of reach of the cams, whereby the valve will not be opened. The arrangement of the guide tongues has further the advantage, that the distributing shaft W undergoes only a small axial displacement, since the cams are not prevented from going back and the inclined ramp at the cams are unnecessary. The present reversing device is suitable for engines with one or more cylinders. The drawings show for instance a double arrangement of the cams on the shaft W for two cylinders.

Having now particularly described and ascertained the nature of the said invention and in what manner the same is to be performed, I declare that what I claim is:

1. In a reversing device for two cycle, internal combustion engines, a hand operated rotary controlling member provided with curved tracks for starting, changing over from the starting to the working position and power regulation, in combination with distributing elements and actuating means operated by the tracks on turning the controlling member, substantially as described. 100

2. In a reversing device for two cycle internal combustion engines, in combination, a hand operated rotary controlling disk provided with curved grooves for starting, changing over from the starting to the working position and for power regulation, distributing elements and means to actuate the latter operated by the grooves on turning the controlling disk, substantially as described. 110

3. In a reversing device for two cycle internal combustion engines, in combination, a hand operated rotary controlling member provided with curved tracks for starting, changing over from the starting to the working position and for power regulation, an axially movable distributing shaft, a lever engaging the starting track connected with the shaft, said shaft being provided with cams for actuating the starting valve and fuel pump of the engine. 115 120

4. In a reversing device for two cycle internal combustion engines, in combination, a hand operated rotary controlling member provided with curved tracks for starting, changing over from the starting to the work- 130

ing position and for power regulation, a lever engaging the track for changing over, a rotary shaft actuated by said lever, and valve levers mounted on eccentrics on said 5 shaft, substantially as described.

5. In a reversing device for two cycle internal combustion engines, in combination, a hand operated rotary controlling member provided with curved tracks for starting, 10 changing over from the starting to the working position and for power regulation, a lever engaged with the track for power regulation, a rotary shaft connected with said lever, and means for controlling the 15 suction valve of the fuel pump through this shaft, substantially as described.

6. In a reversing device for two cycle internal combustion engines, in combination,

a hand operated rotary controlling member provided with curved tracks for starting, 20 changing over from the starting to the working position and for power regulation, the track for changing over provided with outer and inner branches, automatic spring-controlled guide tongues at the end of the 25 inner branches, and means operating the distributing elements by the movement of the controlling member, substantially as described.

In testimony that I claim the foregoing 30 as my invention, I have signed my name in presence of two subscribing witnesses.

HANS WIEDERKEHR.
